UNITED STATES PATENT OFFICE.

MICHAEL C. KELLY, OF MINNEAPOLIS, MINNESOTA.

SEAMLESS-END NECKTIE.

Application filed May 18, 1923. Serial No. 639,781.

To all whom it may concern:

Be it known that I, MICHAEL C. KELLY, a citizen of the United States, residing at Minneapolis, in the county of Hennepin and State of Minnesota, have invented certain new and useful Improvements in Seamless-End Neckties; and I do hereby declare the following to be a full, clear, and exact description of the invention, such as will enable others skilled in the art to which it appertains to make and use the same.

My invention relates to neckties of two ply formation and especially to bow or bat wing neckties.

It is an object of this invention to provide a bow tie which will do away with the thickened seamed portions at the ends of the tie and is provided with folded seamless ends.

It is an additional object to provide such a tie having a very attractive appearance, which will save material and labor in its process of manufacture.

To these ends generally stated, my invention consists of the novel devices and combinations of devices herein described and set forth in the claims.

The invention is illustrated in the accompanying drawings wherein like characters refer to similar parts throughout the several views and, in which,

Fig. 1 is a plan view of the preferred form of my invention;

Fig. 2 is a longitudinal section of the same taken on the line 2—2 of Fig. 1.

Fig. 3 is a cross section taken on the line 3—3 of Fig. 1; and

Figs. 4 and 5 are views similar to Figs. 1 and 2 of a modified form of the invention.

In the preferred form illustrated in Figs. 1 and 2 of the drawings, a suitable blank of fabric is provided having a main or body portion *a* and the end portions *b*. These end portions *b* of the blank are stitched together at *c* and folded back at the proper points on the body portion *a*, forming a two ply tie strip having the folded seamless ends *d*. The longitudinal edges of the superimposed plies are then stitched together, except for a short space left along one edge through which the strip is turned inside out, as is the common practice in the manufacture of ties and then the unstitched edge portion is sewed up by hand to complete the tie.

From the foregoing description, it is obvious that a tie of two ply formation may be constructed out of a single piece of material

with only one joining seam necessary. The common way in use at the present time for making two ply bow ties is to stitch two plies of the same shape together around their edges and ends and then turn the product inside out. This not only leaves seams in the ends of the ties but necessitates about an inch more of material for each tie, since two jointures must be made while only one is necessary in my improved construction. A considerable saving of labor is also effected, since only nine or ten stitches are needed in the one jointure made in the narrow portion of my tie, while about thirty-six stitches are necessary in making two end jointures.

The form shown in Figs. 4 and 5 is made very similar to my preferred form of tie; but employs two short blanks, which are stitched together at the point *e*. The remainder of the process of manufacturing from this point is identical with that employed in the construction of my preferred form, as can be readily seen in Fig. 5. While there is no saving of goods in this form of the invention, short pieces of cloth or the strips necessarily left at the end of a piece of cloth when blanks have been cut out in dovetailed formation, as is the common practice in the tie industry, may be used to make seamless end ties of this form.

The seamless ends give a neater appearance when the bow is tied and do not bunch up or get out of shape, as is often the case with bow ties where the ends are stitched or inturned.

It will, of course, be understood that various changes may be made in the form, details and arrangement of the parts without departing from the scope of the invention.

What is claimed is:—

1. A necktie in the form of an elongated band of sufficient length to surround the neck and have its ends tied in a knot including a pair of tying ends of two ply formation each having a fold constituting a lateral end of the necktie and having seams extending along its longitudinal edges.

2. A necktie in the form of an elongated band of sufficient length to surround the neck and have its ends tied in a knot comprising a single strip of fabric folded laterally at two intermediate points thereof to afford seamless ends of the tie and having seams extending along its longitudinal edges.

3. A necktie comprising a narrow neck so formed will constitute the seamless ends band and relatively wide tying ends formed of a single elongated strip of fabric folded laterally at two intermediate points thereof 5 to afford seamless ends and having its folded portions stitched to the body of the strip along the longitudinal edges thereof.
4. The process of manufacturing a two 10 ply seamless end necktie of sufficient length to surround the neck and have its ends tied in a knot, which consists in stitching the ends of fabric together to form an endless band, flattening out said band to form a two 15 ply strip and leaving the stitched ends at an intermediate portion of the two ply strip, stitching the longitudinal edges of said plies together, whereby the folded ends of the strip
5. The process of manufacturing a two ply 20 seamless end necktie of sufficient length to surround the neck and have its ends tied in a knot, which consists in providing a suitable blank of fabric, folding the ends of said blanks back upon the body thereof to form 25 superimposed plies, stitching the ends of said blank together and also the longitudinal edges of said plies, whereby the folded ends of the blank form seamless ends of the necktie. 30

In testimony whereof I affix my signature.

MICHAEL C. KELLY.
